UNITED STATES PATENT OFFICE.

SOLOMON WILE, OF ROCHESTER, NEW YORK.

SLICING MACHINE.

Application filed May 31, 1923. Serial No. 642,384.

To all whom it may concern:

Be it known that I, SOLOMON WILE, a citizen of the United States, and resident of Rochester, in the county of Monroe and 5 State of New York, have invented certain new and useful Improvements in Slicing Machines, of which the following is a specification.

The present invention relates to slicing 10 machines and more particularly to the type in which there is provided a cutter with a carriage movable back and forth past the cutter and a second carriage having means thereon for clamping the material to be sliced and arranged on the first named carriage to move toward the cutter through the 15 means of a pawl and ratchet mechanism. An object of this invention is to provide a simple and inexpensive means for breaking connection between the carriage and the pawl and ratchet mechanism so that the second mentioned carriage may be moved quickly away from the cutter.

To these and other ends, the invention 20 consists of certain parts and combinations of parts, all of which will be hereinafter described; the novel features being pointed out in the appended claims.

In the drawings:

Fig. 1 is a plan view of a slicing machine constructed in accordance with this invention;

Fig. 2 is a rear view;

Fig. 3 is a fragmentary plan view of the parts in dotted lines;

Fig. 4 is an enlarged section on the line 4-4, Fig. 3; and

Fig. 5 is a perspective view of the detent for holding the rack bar in operative position.

Referring more particularly to the drawings, 1 indicates the main frame, and 2 the cutter mounted to turn thereon, said cutter being connected to a drive shaft 3 in any suitable manner. Mounted to move back and forth on guides 4 on the main frame 1 is a carriage 5. This carriage has in turn a carriage 6 guided thereon to move toward and from the plane of operation of the cutter 7 for clamping the material to be cut by the cutter 2. The mechanism for moving the carriage 5 on the main frame 1 may be of any suitable type and need not be described in detail therein.

The feature of the present invention re-

sides in the mechanism for feeding the carriage 6 on the carriage 5 toward the cutter. This mechanism embodies, in this instance, a bracket 8 secured to the under side of the carriage 5 and having a post 9 projecting upwardly therefrom through an opening 10 in the table. This carries a pinion 11 at its upper end meshing with a gear 12 on the carriage 5 which in turn meshes with a rack bar 13 pivoted at 14 to the under side of the carriage 6 and extending beyond the rear edge of the carriage where it is engaged by a detent 15, that is pivoted at 16 to the carriage 6. It is apparent that this detent holds the rack bar 13 in mesh with the gear 12 and that by moving the detent to release the rack bar the latter may be moved, so that it will be carried out of mesh with the gear 12, thereby permitting the carriage 6 to be moved back and forth independently of the mechanism which effects the movement of the carriage toward the cutter. A spring 17 anchored at 18 to the carriage 6 and at the other end to the rack bar normally tends to move the rack bar out of mesh with the gear 12. The movement of the gear 11 is effected, in this instance, through a ratchet wheel 19 which turns on the post 9. This ratchet wheel is in turn moved by a swinging member 20 which turns loosely on the post and carries a pawl 21. When the carriage 5 approaches one end of its movement on the frame 1, a projection 22 on the frame 1 will engage the swinging member 20 and shift the latter against the action of a spring 23 which is secured to a deflected end 24 of the swinging member and to the carriage 5, causing the tooth 21 to engage the ratchet wheel 19 and shift the latter and the pinion 11 any desired amount.

With the end in view of varying the feeding action of the table or carriage 6 toward the cutter, an adjusting mechanism is provided which comprises, in this instance, a hand wheel 25 mounted to turn about an upright axis on the table 5 and having an arm 26 extending therefrom and connected by a link 27 to a controlling member 28, such as shown in my application No. 612,615 filed January 15, 1923, this controlling member cooperating with a pin or projection 29 on the pawl 21 and holding said pawl out of cooperation with the ratchet wheel 19 until such a time that the time of engagement between the pawl and the ratchet wheel will

be sufficient, during the shifting of the swinging member 20 by the operating projection 22, to effect that amount of turning in the ratchet wheel necessary to feed the 5 table or carriage 6 the desired amount.

From the foregoing it will be seen that there has been provided a slicing machine having a mechanism for feeding a carriage toward a cutting mechanism and in which 10 there is employed a pawl and ratchet geared to a rack bar on the carriage, said rack bar being movable out of connection with the pawl and ratchet mechanism so that the carriage may be moved independently of the 15 pawl and ratchet mechanism by hand away from the cutting mechanism. The rack bar is pivotally mounted and is held in operative position by a detent.

What I claim as my invention and desire 20 to secure by Letters Patent is:

1. In a slicing machine, the combination with a cutter, a carriage movable back and forth past the cutter and a second carriage movable on the first named carriage toward 25 the cutter, of mechanism for moving the second named carriage on the first named carriage comprising a pawl and ratchet

mechanism mounted on the first named carriage, a gear driven by the pawl and ratchet, and a rack bar mounted on the second mentioned carriage and meshing with said gear, said rack bar being movable out of engagement with the gear to permit the second mentioned carriage to be moved away from the cutter.

2. In a slicing machine, the combination with a cutter, a carriage movable back and forth past the cutter and a second carriage movable on the first named carriage toward the cutter, of mechanism for moving the second named carriage on the first named carriage comprising a pawl and ratchet mechanism mounted on the first named carriage, a gear driven by the pawl and ratchet, and a rack bar mounted on the second mentioned carriage and meshing with said gear, said rack bar being pivotally mounted on the second mentioned carriage and extending to one side of the second mentioned carriage to permit it to be moved out of engagement with the gear, and means for holding the rack bar in such engagement.

SOLOMON WILE.
